INVENTOR:
Claudius Dornier

UNITED STATES PATENT OFFICE.

CLAUDIUS DORNIER, OF FRIEDRICHSHAFEN, GERMANY, ASSIGNOR TO ZEPPELIN-WERKE LINDAU, GESELLSCHAFT MIT BESCHRANKTER HAFTUNG, OF LINDAU-REUTIN, GERMANY, A GERMAN CORPORATION.

FLYING-MACHINE CARRIAGE.

Application filed March 31, 1921. Serial No. 457,545.

To all whom it may concern:

Be it known that I, CLAUDIUS DORNIER, a citizen of the German Empire, residing at Friedrichshafen, Germany, have invented 5 certain new and useful Improvements in Flying-Machine Carriages (for which I have filed an application in Germany, May 24, 1920), of which the following is a specification.

10 My invention relates to flying machines and more especially to the carriages thereof and its particular object is to avoid the drawbacks connected with the carriages hitherto in use. The provision of a carriage 15 as is well known to those familiar with the art, involves numerous drawbacks which it has been endeavored to overcome or to at least minimize in manifold ways. One of the main defects resides in the objectionable 20 air resistance thereby created. It has been suggested, to reduce this objectionable resistance by arranging the carriage so as to be capable of being drawn in; this, however, results in an additional disadvantage, 25 namely, of causing an increase in weight, so that the practical results thereby obtainable are rendered rather doubtful. Again the almost unavoidable breaking of the carriages of the type hitherto used in the event of 30 rough landings, generally occasioned serious injury to the machine, since the very height of the carriage often favoured the liability of capsizing.

My invention is intended to remedy these 35 defects by the hull of the flying machine being disposed so low that the substantially horizontal wheel axle can be directly connected to the hull, the carriage proper being entirely eliminated. The axle may in 40 this case be constructed so as to form rigid fin-shaped, extensions projecting laterally from the hull, or else it may consist of an undivided entirety running right through from wheel to wheel, or also just extend to 45 the sides of the hull and be there lodged to rotate.

By these means there is provided a starting device which, while embodying lightness of weight and least possible resistance 50 to the air, will offer the utmost safety even in the case of rough landings, since the possibility of the machine capsizing is rendered

practically impossible even in case the starting device should happen to break.

In the drawings affixed to this specification and forming part thereof, two modifications of a flying machine hull embodying my invention are illustrated by way of example. In the drawings

Fig. 1 is a sectional view on line A—A in 60 Fig. 2, of an arrangement comprising a shaft running right through from wheel to wheel.

Fig. 2 is a corresponding longitudinal view.

Fig. 3 shows a modified form of arrangement.

Referring to the drawings, the hull *a* carries on either side a fin-shaped reinforcing member *b* enclosing the wheel axle *c* with 70 wheels *d*. The shock absorbers, denoted by *e*, extend from the points of attachment *f* at the lower inside wall of the reinforcing member *b* across the axle, so that the space intermediate the axle and the upper wall is 75 available for the tightening thereof.

The axle shown in Fig. 3 is made in two parts. At the side walls of the hull *g* there are arranged links *h* permitting the axle sections *i* to execute a movement transverse- 80 ly to the axis of the hull.

Movement in this direction is limited to the suitable degree by the shock absorbers *l* arranged within the fin-shaped reinforcing members.

I have found it expedient to limit the working of the springs or shock absorbers in the customary manner in order to prevent any excessive resiliency and to insert at suitable places elastic layers between the parts 90 as an additional means of protection for the wheel axle and the rigid extension members.

When employing the construction according to Figs. 1 and 2 in connection with light aircraft, special shock absorbers may, if preferred, be omitted altogether and the resiliency relied upon exclusively which is provided by the material of which the wheel axle is made.

I claim:

1. A flying machine comprising in combination, a hull, wheel axles extending on either side of said hull and substantially on a level with its bottom, substantially tubu-

lar shells fixed to said hull and surrounding said axles and resilient shock absorbing means within said shells adapted to relieve said axles of the strain acting thereon.

5 2. A flying machine comprising in combination, a hull, wheel axles extending on either side of said hull and substantially on a level with its bottom, and linked to said hull, sub-

stantially tubular shells fixed to said hull and surrounding said axles and resilient 10 shock absorbing means within said shells adapted to relieve said axles of the strain acting thereon.

In testimony whereof I affix my signature.

CLAUDIUS DÖRNIER.
